Benage S. Josselyn INVENTOR

UNITED STATES PATENT OFFICE.

BENAGE S. JOSSELYN, OF DENVER, COLORADO.

DESIGN FOR A SOUVENIR SPOON.

SPECIFICATION forming part of Design No. 21,347, dated February 16, 1892.

Application filed December 14, 1891. Serial No. 415,049. Term of patent 3½ years.

To all whom it may concern:

Be it known that I, BENAGE STOCKWELL JOSSELYN, a citizen of the United States, residing at Denver, in the county of Arapahoe and State of Colorado, have invented and produced a new and original Design for Spoons, of which the following is a specification, reference being had to the accompanying drawings, showing the whole thereof.

10 Figure 1 is a front or face view of a spoon, and Fig. 2 an edge view, these two views being deemed necessary to fully illustrate my design.

15 The leading feature of my design consists in raised-work surface, the outlines of which, when viewed in elevation, as in Fig. 1, will represent various distinct figures.

20 A is the head of the spoon, which represents a man in armor on horseback in bas-relief.

B is the center of the handle and represents a crown pierced diagonally by two crossed swords.

Upon the four wings of the Maltese cross are certain figures consisting of a skull and cross-bones, square and compass, setting-maul and chisel, and on the fourth side two triangles so interlaced as to produce a six-pointed star. In the center of the cross is inscribed a circle, and in the center of said circle is placed a Passion cross in upright position. 25 Surrounding this design, which is placed in the bowl of spoon, are the words "Silver Triennial Conclave, Denver, 1892," all in raised work. It is obvious, however, that such words and dates may be omitted, as not being of the 30 essence of my design.

What I claim is —

The design for a spoon, herein shown and described.

BENAGE S. JOSSELYN.
